UNITED STATES PATENT OFFICE.

STEVE ZUNAC, OF COALDALE, PENNSYLVANIA.

SAFE-ALARM.

1,238,618.

Specification of Letters Patent. Patented Aug. 28, 1917.

Application filed December 8, 1916. Serial No. 135,828.

To all whom it may concern:

Be it known that I, STEVE ZUNAC, a citizen of the United States, residing at Coal-
dale, in the county of Schuylkill and State
of Pennsylvania, have invented certain new
and useful Improvements in Safe-Alarms, of
which the following is a specification.

The present invention relates to certain
new and useful improvements in alarm de-
vices, and has for its object to provide a
device of this character which may be used
in connection with either the closures of
small containers such as safe deposit boxes,
jewel boxes, etc., or large doors or closures
such as are found upon vaults or safes.

Further objects of the invention are to
provide a device of the character described
which embodies novel features of construction
whereby a series of audible alarms are
operated when an attempt is made to oper-
ate the lock controlling the closures of safe
deposit boxes, vaults, safes, or the like, and
whereby alarms are sounded while the lock
mechanism is being operated and when the
closure is opened.

Still further objects of the invention are
to provide novel means whereby when the
alarm is used in connection with small con-
tainers, an audible signal is sounded both
when the container is lifted from a support,
and while the same is being transported
from one place to another.

Another object of the invention is to pro-
vide a device of the character described
which is simple and inexpensive in its con-
struction and which will render an article
to which it is applied safe from unau-
thorized tampering therewith without the
knowledge of persons within hearing dis-
tance thereof.

With these and other objects in view, the
invention consists in certain novel combi-
nations and arrangements of the parts as
will more fully appear as the description
proceeds, the novel features thereof being
pointed out in the appended claims.

For a full understanding of the inven-
tion, reference is to be had to the following
description and accompanying drawings, in
which:—

Figure 1 is a front elevation of a safe
deposit box having an alarm constructed
in accordance with the invention applied
thereto.

Fig. 2 is a rear elevation drawn upon an

enlarged scale of the rear side of the front
of the box, portions being broken away.

Fig. 3 is a longitudinal horizontal sec-
tional view through the box casing, the
alarm and locking mechanism connected
therewith being shown in top plan view.

Fig. 4 is a front elevation of the box, por-
tions being broken away and shown in sec-
tion.

Fig. 5 is a transverse vertical sectional view
through the box taken on the line 5—5
of Fig. 3.

Fig. 6 is an elevation of one side of the
box, the door therein being removed.

Fig. 7 is a view similar to Fig. 6 of the
opposite side of the box, portions being
broken away and shown in section.

Fig. 8 is a view similar to Fig. 2, showing
a shutter mechanism for the opening in the
front of the box.

Fig. 9 is a vertical sectional view through
a portion of the top of a table or other sup-
port upon which the box must be placed
before access can be had to the mechanism
through the opening in the front of the box.

Corresponding and like parts are referred
to in the following description and indicated
in all the views of the drawings by the same
reference characters.

For the purpose of illustration the inven-
tion is shown as applied to a container of
the safe deposit box type, and the alarm
mechanism is operatively connected with a
sliding drawer therein, although it will be
obvious from the following description that
the invention could as well be used in con-
nection with the doors of safes and the like.
In the present instance the alarm mechanism
is shown as fitted within a chamber sepa-
rated from the sliding drawer, although
with very slight modification it could be di-
rectly applied to the drawer or any other
closure, and the operation would be substan-
tially the same in any case.

Referring to the drawings, the character
A designates a safe deposit box having a
sliding drawer 12 mounted in the front 1
thereof. A swinging arm 3 is mounted
upon the inside of the front 1, and in the
present instance is shown as rigidly con-
nected with the spindle 4 of a conventional
permutation lock 5, the object of connecting
this swinging arm 3 to a permutation lock
being to prevent movement of the arm un-
less the correct combination of the lock is

known to the operator. No claim is made to the construction of the permutation lock, however, and any conventional construction of lock, such as a dial lock, a push pin lock, or a knob pin lock, may be used, the only requisite being that the arm 3 be operatively connected with the lock so that the arm may be swung upwardly when the lock is manipulated in the proper manner. It is contemplated to use the lock described in my copending application filed November 17, 1916, Serial No. 131,876, which lock embodies a swinging tumbler similar to the swinging arm 3 as illustrated by Fig. 2. A coil spring 8 normally tends to pull the arm 3 downwardly to a substantially horizontal position, the downward movement of the arm being limited by a stop pin 9. An opening 10 extends entirely through the front 15 of the box, the said opening being of a diameter slightly greater than the index finger of the human hand, the said opening providing access to the alarm mechanism within the box, and the said alarm mechanism can be successfully operated by an authorized person merely by the insertion of the index finger through this opening and a proper manipulation of certain of the parts of the mechanism by the finger, as will be hereinafter more fully described. A swinging closure plate 11 is pivoted upon the front of the box adjacent the opening to 10, and may be swung over the opening to provide a closure therefor when access is not desired to the mechanism within the box.

The box A is horizontally divided into two compartments B and C, the compartment B being adapted to receive the alarm mechanism, and the compartment C, the sliding drawer 12. Access to the interior of the compartment B is had from the top thereof by swinging the cover D, which is hingedly connected at 13 to the rear side of the box, connected at 13 to the rear side of the box, upwardly. This cover is normally locked against opening by means of the latch 14 mounted upon the front of the box. The said latch 14 comprises a substantially horizontally disposed lever 14^a which is pivotally mounted at an intermediate point in its length at 14^b to the inside of the front of the box, near the top thereof. One end of the lever 14^a is provided with a hooked finger 14^c adapted to engage an eye 14^d which is secured to the inside of the top D of the box. The other end of the lever 14^a has pivotally connected thereto a substantially vertically disposed rod 14^e which is slidably mounted in a guide member 14^f secured to the front of the box. The lower end of the rod 14^e extends downwardly into the chamber C, and is provided with a returned finger piece 14^g. A coil spring 14^h normally tends to force the hooked finger 14^c into engagement with the eye 14^d to lock the cover D, and the cover can not be unlocked until the drawer 12 is opened, when a downward pull upon the finger piece 14^g will withdraw the hooked finger 14^c to unlock the cover.

It is contemplated to provide means whereby the alarm mechanism may be removed from the box A as an entirety, for the purpose of facilitating the adjustment and repair thereof, and in the present instance the mechanism is shown as mounted within a sub-container E which comprises a bottom 15 and sides 16. A drum 17 is mounted within this sub-container E so as to rotate about a vertical axis, the said drum being provided with heads 18 which carry the pivot studs 19, the pivot stud on the lower head being journaled within the bottom of the sub-container E, while the stud 19 on the upper head is journaled within a transverse bar 20 which has its opposite ends secured to the sides 16. The heads of the drum are connected by a plurality of slats 21, the said slats being shown as arranged in spaced intervals about the periphery of the drum, so as to provide longitudinal openings 23 therein. A plurality of threaded openings 24 are provided in the upper head of the drum, the said openings being arranged in a peripheral row, and one of said openings being disposed in substantial alignment with each of the openings 23 in the periphery of the drum. A threaded catch pin 25 is adapted to be screwed into any selected one of the openings 24, the said pin being shown as constructed similarly to a screw so as to be easily and quickly removed from one opening and placed in another, as may be desired. One or more knobs or projections 26 are arranged upon the longitudinal sides of the openings 23 in the periphery of the drum 17, the number of said knobs 26 being different upon each opening. When the pin 25 is inserted in any one of the openings 24, notice is taken of the number of knobs 26 in the opening 23 at a diametrically opposite point on the drum from the pin 25; so that when the drum is rotated in order to bring the said opening 23 to the front of the box it will be known that the pin 25 is at a diametrically opposite point on the rear side of the drum. The drum is adapted to be rotated by the insertion of the index finger of the hand through the opening 10 in the front of the box, and into the various openings 23 in the periphery of the drum, and the drum is arranged to operate in a clockwise direction, since this is easier done than to rotate the drum in a counterclockwise direction. As the drum is rotated the number of knobs 26 on the various openings 23 can be easily ascertained by feeling therefor with the finger. The pin 25 on the drum 17 when it reaches the rear side of the drum is adapted to operate with an operating lever 27 which is pivotally connected at 28 to a transverse

bar 29 extending between the sides 16 of the container E. The forward end of the said operating lever 27 is provided with an opening 30 of substantially the same size as the pin 25, and when the lock is being operated the lever 27 is forced downwardly to bring the opening 30 into engagement with the pin 25. The outer end of the lever 27 is normally held in a position to clear the top 10 of the pin, by means of a leaf spring 31 mounted thereunder upon the transverse bar 29. The pivot bolt 28 is slidably mounted within a slot 32 in the transverse bar 29, and is normally held at the rear end of said slot 15 by means of a spring 33 acting upon a loop 34 connected to the pivot bolt.

A pair of cables or cords 35 are connected to the rear of the loop 34 and pass rearwardly over pulleys 36 secured to the rear 20 side of the box A, and then downwardly over pulleys 37 to a pair of sliding locking bolts 38 which coöperate with a looped keeper 39 projecting rearwardly from the drawer 12 to lock the drawer in a closed position. No 25 claim is made to the construction of these locking bolts 38, they being of a conventional construction, and being slidably mounted in casings 40 and normally forced outwardly into operative position by coil 30 springs 41. When the lever 27 is brought into engagement with the pin 25 on the drum 17, the drum is rotated in a clockwise direction, which action moves the pin toward the front of the box, and in turn pulls 35 the pivot bolt 28 forwardly in the slot 32. As the bolt 28 moves forwardly the loop 34 pulls upon the cables 35 which in turn simultaneously withdraw the locking bolts 38 from engagement with the looped keeper 39 40 on the drawer 12. A coil spring 42 has one end thereof secured to the front wall of the box A, and the other end thereof secured to the drawer 12 at 43, and when the bolts 38 are withdrawn from the looped keeper 39 45 the spring 42 forces the drawer outwardly into an open position.

For the purpose of forcing the operating lever 27 downwardly against the action of the spring 31 into engagement with the pin 25 on the drum 17, a horizontally disposed lever 44 is pivotally mounted at 45 upon one side 16 of the container E, and extends transversely across the top of a lever 27, being pivotally connected at its other end 50 to a link 46 which is in turn pivotally connected to a lever 47 which extends longitudinally along the opposite side 16 of the container E, the said lever 47 being pivotally connected at its rear end to the said side 16 at 48. The forward end of the lever 47 is pivotally connected at 49 to a link 50 which extends upwardly at the front of the box in close proximity to the door 1, and is pivotally connected at 51 to one end of a lever 52, the opposite end of which is pivot-

ally connected at 53 to the first mentioned side 16 of the container E. The lever 52 is arranged above the opening 10 in the door 1, and in order to operate the same from the opening, a finger bar 54 is suspended adjacent the opening 10 from the lever 52, by means of links 55. When the finger bar 54 is forced downwardly this action is transmitted through the leverage above described to the lever 44, which in turn forces the lever 27 downwardly. It will be understood that the finger bar 54 must be forced downwardly simultaneously with the rotation of the drum 17, in order to withdraw the locking bolts 38 from the keeper 39 on the drawer 12. If the drum alone is operated the pin 25 will slip under the lever 27 which is held above the pin by the spring 31, and if the finger bar 54 alone is operated the pivot bolt 28 will not be drawn forwardly 85 in the required manner.

It will be obvious that it is necessary that a predetermined point be provided for where the opening 30 in the lever 27 will slip over the pin 25, and this point in the present instance is diametrically opposite the center of the front of the drum. In order to make it practically impossible for the drawer 12 to be opened without knowledge of the full operation of the mechanism, and to move the lever 27 about its pivot into the proper position, an index bar 56 is provided, the said index bar being pivotally mounted at its rear end to the transverse bar 29 at 57. A worm shaft 58 extends 100 transversely across the container E and has its ends journaled in the sides 16 thereof, and the index bar 56 engages the threads of the said worm shaft 58 so that rotation of the worm shaft will cause an oscillation 105 of the index bar about its pivot 57. A U-shaped yoke 59 passes through the index bar 56, the arms of the said U-shaped yoke extending downwardly upon opposite sides of the operating lever 27, as clearly shown by Fig. 5. The base of the yoke 59 passes loosely through the index bar 56, and is threaded to receive jam nuts 60 to clamp the same in position on the index bar. With this arrangement the arms of the yoke may 110 be adjusted so as to bring them nearer to or farther away from the sides of the index bar 56, for a purpose to be hereinafter described. The front end of the index bar 56 is provided with a weight 61, the purpose of which is to hold the bar in engagement with the worm shaft. The outer end of the index bar 56 is also provided with a downwardly suspended clapper ball 62, which is adapted to engage a pair of inverted bells 63 mounted upon the transverse bar 20. This clapper ball is supported by a flexible link 64 which is long enough to allow the clapper ball to fall within either of the bells 63, as shown by Figs. 3 and 4. 130

When the worm shaft 58 is rotated in a clockwise direction with the index arm in the position indicated by Fig. 3, the index bar will be moved toward the center of the box A, and after it has been moved a sufficient distance the clapper ball 62 will be pulled out of the bell 63 and over the upper edge thereof, and then owing to the action of gravity will fall so as to strike the side of the opposite bell 63, thereby producing a ringing sound. The two bells 63 are of different resonances, and an authorized operator will know by the sound produced by the falling of the clapper ball in which direction the index bar 56 is being moved. As the index bar is moved, one of the arms of the yoke 59 will engage the operating lever 27, so as to move the same in the same direction. It will be noted from reference to Fig. 3 that one of the arms of the yoke 59 is nearer the index bar 56 than the other, and that therefore the said arm of the yoke will come into engagement with the lever 27 sooner than would the opposite arm of the yoke were the index bar in the corresponding position on the opposite side of the center of the box.

With the yoke 59 arranged as shown in Fig. 3, movement of the index bar 56 toward the center of the box until the clapper ball 62 falls from the bell with which it is now in engagement to the other bell, will bring the opening 30 of the lever 27 in exactly the right position to engage the pin 35 on the drum 17 to operate the bolts 38. It will be obvious, however, that were the clapper ball 62 in engagement with the opposite bell and the index bar 56 in a corresponding position, that movement of the index bar until the clapper ball struck the other bell would not bring the opening 30 of the lever 27 quite up to the proper position, owing to the difference in the distance of the other arm of the yoke from the index bar. With the construction described it will be seen that the action may be reversed by merely adjusting the yoke 59 to the proper position on the index bar 56.

For the purpose of rotating the worm shaft 58, a pulley wheel 64 is rigidly applied thereto, said pulley wheel being connected by a flexible belt 65, such as a coil spring belt, to a pulley 66 rigidly connected to a transversely disposed shaft 67 arranged adjacent the opening 10 in the door. This shaft has its ends journaled in bearings 68 on the sides 16 of the container E and is provided for a portion of its length nearest the opening 10 with an enlarged and knurled portion 69 to facilitate the rotating thereof by the finger.

Means have been provided whereby the lever 27 can not be forced into engagement with the pin 25 even though the pin 25 and lever 27 had been by accident actuated into the proper positions, unless the combination

of the permutation lock 5 is known to the operator. A horizontally disposed lever 70 has one end thereof pivotally connected at 71 to one side 16 of the container E, and is provided at a point adjacent the center of 70 the drum 17 with a laterally projecting enlargement 72, the said enlargement 72 being normally forced by a spring 73 to a point under the end of the lever 27 so that the lever will strike the same and be prevented 75 from engaging the pin 25. The free end of the lever is connected by a link 74 to one arm of a bell crank lever 75 pivotally mounted upon a vertically disposed standard 76, the opposite arm of said lever being adapted to 80 normally engage the top of the swinging arm 3 on the door 1. When the combination of the lock 5 is known and the lock is operated in the proper manner so as to raise the swinging arm 3, the upward movement of the 85 swinging arm is transmitted to the bell crank lever 75 and link 74 so as to withdraw the enlarged portion 72 of the lever 70 from beneath the end of the operating lever 27. After the drum 17 has been rotated to bring 90 the pin 25 into the proper position, and the lever 27 has been moved into proper position to engage the pin, the lock 5 is operated so as to raise the arm 3 and withdraw the enlarged portion 72 of the lever 70 from beneath the end of the lever 27, after which the lever 27 may be forced into engagement 95 with the pin and the drum rotated in the required manner to withdraw the bolts 38.

For the purpose of sounding a series of 100 alarms as the drum 17 is rotated so as to signal the unauthorized tampering with the safe deposit box, a gear wheel 77 is journaled between the bottom of the container E and a transverse bar 78, the teeth of the said gear wheel meshing with the openings 23 in the drum 17. An alarm bell is mounted on the top of the transverse bar 78, said alarm bell 79 being sounded by rotation of the gear wheel. No claim is made to this bell, it being 105 of conventional construction and including a gear wheel 80 rigidly connected to the pivot stud of the gear wheel 77, said gear wheel 80 meshing with a pinion 81 which is rigidly connected with a gear wheel 82 which 110 in turn meshes with a pinion 83 rigid with a shaft 84 carrying the conventional clappers 85. As the gear wheel 77 is rotated by rotation of the drum 17, the clappers 85 are actuated in the usual manner to strike the 115 bell 79 to sound an alarm. A pair of gongs 86 are rigidly secured to the sides 16 of the container E, and a pair of spring strips 87 are secured adjacent the gongs, one strip 120 for each gong, the said strips serving as clappers for the gongs. The free ends of the spring strips 87 project into the path of the teeth of the gear wheel 77, and as the gear wheel 77 is rotated the spring strips are first sprung back and then released to strike the 125 gongs. The free ends of the spring strips 87 project into the path of the teeth of the gear wheel 77, and as the gear wheel 77 is rotated the spring strips are first sprung back and then released to strike the 130 gongs.

gongs as the teeth pass by the ends of the strips.

A large gong 88 is arranged at the top of the box A and immediately under the cover 5 D thereof, and a clapper 89 therefor is rigidly secured to the upper end of a vertically disposed clapper shaft 90, the lower end of which is rotatably received within a vertical bearing sleeve 91. An actuating arm 92 projects from the clapper shaft 90 into engagement with the gear wheel 77, through an opening in the bearing sleeve 91. A spring 93 has one end thereof connected to this actuating arm, and the other end thereof 10 of to the bottom of the container E, said spring normally forcing the clapper 89 into engagement with the gong 88. As the gear wheel 77 rotates the teeth thereof engage the actuating arm 92 of the clapper shaft 90 to force the clapper 89 away from the gong, and as the teeth pass by the actuating arm the spring 93 acts to quickly bring the clapper 89 back into engagement with the gong 88, so as to produce a loud sound. It will 20 thus be seen that each time the drum 17 is rotated a distance of one opening 23, one of the gongs 86 and 88 will be sounded, and that when the drum 17 is rotated rapidly 25 all of the gongs 86 and 89, and the bell 79 will be sounded, the gongs in rapid succession and the bell 79 continuously.

Means have also been provided whereby an alarm is sounded when the drawer 12 is opened, said means comprising a sliding pin 35 95 which is mounted within a guide 96, one end of the said pin being adapted to engage the back of the drawer, while the other end thereof has connected thereto a wire or cord 97 which extends upwardly along the side 40 of the box to the operating lever of a clapper operating mechanism 98 arranged within a vertically disposed compartment F provided in one side of the box A. The operating lever of the said clapper mechanism is pivotally connected at 99 to the side of the box A, and is provided at the end thereof opposite that to which the wire 97 is connected with a segmental rack 100 which meshes with a pinion 101 pivotally mounted 45 on a pivot pin 102 and carrying the usual clappers 103. When the drawer 12 is forced into a closed position against the action of the spring 42, the pin 95 is forced rearwardly thereby so as to oscillate the operating lever of the clapper mechanism to actuate the clappers and when the drawer is forced outwardly into open position the operating lever is oscillated in the opposite direction by a spring 104 which also pulls the pin 95 forwardly. The clappers 103 are brought into engagement with a bell 105 each time the drawer is opened and closed.

To sound an alarm when the box A is moved from a support, an actuating pin 106 50 is slidably mounted in a bearing 107 se-

cured to the side of the box A, said pin being provided with a reduced inner end portion 108 which passes through an elongated slot 109 in the free end of a lever 110 pivotally mounted at one of its ends at 111 to the end of the box A. The pin 106 is normally in the position indicated by Fig. 7, when the box is not resting upon a support, and is forced into this position with the outer end thereof projecting beyond the bottom of the box by means of a coil spring 112. The lever 110 engages at an intermediate point in its length a bell actuating slide 113, the said slide being bifurcated, and one of the arms of the bifurcation provided with a rack 114 which meshes with a gear 115 rotatably mounted upon a pivot pin 116, the said gear wheel 115 being provided on its upper side with a pawl 117 which engages a ratchet 118 loosely mounted on the pivot pin and which carries the conventional clappers 119. When the actuating slide 113 is forced upwardly the pawl 117 slips by the teeth of the ratchet 118, although when the actuating slide 113 is moved downwardly, or out of the bell 105, the pawl 117 positively engages the ratchet 118 so as to rotate the clappers 119 to sound the bell 105 in the usual manner. The actuating slide 113 is normally forced outwardly by means of a spring 120. When the box A with the pin 106 in the position shown by Fig. 7 is set upon a support, the lever 110 is forced upwardly, which in turn forces the actuating slide 113 upwardly, and when the box is then picked up from the support the springs 120 and 112 force the mechanism into the position shown by Fig. 7, thus sounding the bell 105.

Means have also been provided for sounding an alarm when the box A is being transported from place to place. A pair of gongs 121 are rigidly secured to the side of the box A opposite that upon which the bell 105 is mounted, and are arranged within a compartment G, similar to the compartment F. A clapper mechanism identically the same with the clapper mechanism 98 is also secured to the side of the box adjacent the gongs 121, the operating lever being designated by the numeral 122, the segmental rack thereon by 123, and the pinion carrying the clappers 124 by the numeral 125. The free end of the lever 122 is pivotally connected to a vertically disposed link 126 which is connected to one end of a substantially horizontally disposed lever 127 pivoted at an intermediate point in its length at 128 to the side of the box A. The opposite end of the lever 127 has suspended therefrom, by means of a link 129, a weight 130, the said weight normally resting upon a spring strip 131 secured to the box A. As the box A is transported, the up and down movement incident thereto causes the weight 130 130

to reciprocate up and down so as to oscillate the lever 127. This movement is transmitted to the operating lever 122 of the clapper mechanism so that the clappers 124 are brought into engagement with the gongs 121 so as to sound the same. The up and down movement of the weight 130 is magnified by the spring 131, so that the least movement of the box in a vertical direction will cause the 10 gongs 121 to be sounded. No claim is made to any of the clapper mechanisms above described, and it is contemplated to use any desirable form of mechanism, although the above have been included merely for the 15 purpose of illustration.

Both of the compartments F and G are provided with doors 132 for the purpose of inspecting the alarm mechanisms in the compartments, and any desired form of 20 locking means may be provided therefor such as the hooks and eyes 133, which can only be operated from the interior of the box.

It is desirable to provide means for automatically closing the opening 10 in the front of the box so as to prevent manipulation of the mechanism within the same, and thereby preclude all possibility of an accidental successful operation of the mechanism to unlock the drawer 12. For this purpose a shutter 135 is shown as pivotally mounted upon the inside of the front 1 of the box and adapted to swing across the opening 10. The shutter comprises a lever 25 pivotally mounted at an intermediate point in its length at 136 to the front of the box, the outer end of said lever being of an elongated arcuate formation, as indicated at 137, and provided with an opening 138 disposed at substantially the center thereof, the said opening being of substantially the same diameter as the opening 10. When the shutter lever is swung to either side it covers up the opening 10 in the front of the box, although when the lever is disposed at its 30 central position the opening 138 therein registers with the opening 10 so as to allow access to the mechanism in the box. The opposite end of the shutter lever 135 has pivotally connected thereto at 139 one end of a link member 140, the opposite end of said member being pivotally connected to a laterally projecting arm 141 rigidly connected to an operating lever 142, one end of which is 35 pivotally connected at 143 to the inside of the front 1 of the box. This lever 142 extends along the inside of the front 1 and into the compartment F at one side of the box, being then offset at 144 and having a pin and slot 40 connection 145 with the outer end of the alarm operating lever 110. A coil spring 146 normally tends to draw the outer end of the lever 142 into the position shown on the drawings. When the pin 106 is forced outwardly to its limit, as indicated by Fig. 7,

the lever 142 is operated to swing the shutter lever to one of its extremes, as indicated on the drawing, so as to close the opening 10, and when the pin 106 is forced inwardly to its limit, the lever 142 swings the shutter lever 135 to its opposite extreme so as to also close the opening 10. However, when the pin 106 is moved to an intermediate point in the length of its travel, the lever 142 is so operated as to swing the shutter lever 135 to its central position, thus bringing the opening 138 therein into registry with the opening 10. The shutter lever is guided in its movements by a guide flange 146 secured to the inside of the front 1 of the box and engaging the upper edge of the shutter lever, and this guide flange prevents the forcible displacement of the shutter lever from over the opening 10.

The pin 106 may be held in the required intermediate position in any suitable manner, although in the present instance a table or other support 150 is shown as provided in the top thereof with a depression or recess 151, the depth of which is substantially one-half of the length of the travel of the pin 106. When the box A is placed upon the support 150 and the pin 106 is allowed to drop into the opening 151 the shutter lever 135 is automatically swung to a central position so as to allow access to the mechanism through the opening 10. In view of the fact that the pin 106 is connected to the alarm operating lever 110 it will be obvious that any attempt to move the pin or the shutter 135 so as to open the opening 10, will be 50 closed by the ringing of the alarm bell 105.

Having thus described the invention, what I claim as new and desire to secure by Letters Patent, is:—

1. The combination with a container having a closure therein and a lock mechanism for the closure, of means for intermittently sounding one alarm during each movement of the lock mechanism, and means for sounding a second and different alarm continuously and simultaneously with the first mentioned alarm during a prolonged movement of the lock mechanism.

2. The combination with a container having a closure therein and a lock mechanism for the closure, of means for singly sounding an alarm instantly upon each slight movement of the lock mechanism, and means for intermittently sounding the same alarm during a prolonged movement of the lock mechanism.

3. The combination with a container having a closure therein and a lock mechanism for the closure, of means for sounding one alarm singly upon each slight movement of the lock mechanism, mean for sounding the same alarm intermittently and successively during each material movement of the lock mechanism, and means for sounding a sec-

ond and different alarm continuously during each material movement of the lock mechanism.

4. The combination with a container having a closure therein and a lock mechanism for the closure, of means for sounding a single alarm upon each slight movement of the lock mechanism, and means for continuously sounding a second and different alarm during each material movement of the lock mechanism.

5. The combination with a container having a closure therein and a lock mechanism for the closure, of a gear wheel journaled in the container and adapted to be rotated by the actuation of the lock mechanism, an alarm mechanism rigidly connected to said gear wheel so that rotation of the gear wheel causes a sounding of the alarm, and a second alarm mechanism actuated by the teeth of the gear wheel as the same is rotated.

6. The combination with a closure, of a rotatable drum having a plurality of openings in the periphery thereof, a pin carried thereby, a lock for the closure, an operating lever adapted to coöperate with the said pin on the drum to actuate the said lock, a gear wheel the teeth of which mesh with the said opening in the periphery of the drum, and an alarm actuated by said gear wheel when the drum is rotated.

7. The combination with a closure, of a rotatable drum, means for locking the said closure, means operated by the drum for actuating the said lock for the closure, and an alarm actuated by the rotation of the drum.

8. The combination with a closure, of a rotatable drum having a plurality of openings in the periphery thereof, a lock for the closure, means actuated by the drum for operating the said lock for the closure, a gear wheel the teeth of which mesh with the said openings in the drum, and an alarm actuated by the teeth on the gear wheel when the said drum is rotated.

Copies of this patent may be obtained for five cents each, by addressing the "Commissioner of Patents, Washington, D. C."

9. The combination with a closure, of a lock therefor, means for operating the lock, an alarm mechanism, a sliding pin adapted to engage the closure when the same is in a closed position, a link member connecting the sliding pin with the alarm mechanism, and a spring for sliding the pin in the direction of the opening of the closure, so that when the closure is opened an alarm is sounded through actuation by the spring, and when the closure is closed by engagement thereof with the sliding pin.

10. The combination with a container having an opening in one wall thereof, of a shutter mounted upon the inside of the said wall and adapted to swing over the opening therein, an alarm mechanism, and an operative connection between the shutter and the alarm mechanism, so that movement of the shutter sounds the alarm.

11. The combination with a closure and a lock therefor including a rotatable drum, of a wheel actuated by the said drum and having a serrated periphery, a gong, and a clapper for said gong, one end of said clapper being fixed, while the other end thereof engages the serrated periphery of the before-mentioned wheel, so that as the wheel rotates the clapper is successively engaged and released by the serrations on the wheel to produce successive soundings of the gong.

12. The combination with a closure and a lock therefor including a rotatable drum, of a wheel rotated by the said drum and having a serrated periphery, a gong, and a clapper for said gong, said clapper engaging the serrated periphery of the before-mentioned wheel, so that as the wheel rotates the gong is successively sounded by the clapper.

In testimony whereof I affix my signature in the presence of two witnesses.

STEVE ZUNAC.
